UNITED STATES PATENT OFFICE

139,936

DESIGN FOR AN OVER AND UNDER INDICATOR FOR A WEIGHING SCALE

Henry Dreyfuss, New York, N. Y., assignor to Fairbanks, Morse & Co., Chicago, Ill., a corporation of Illinois

Application July 20, 1944, Serial No. 114,468

Term of patent 14 years

(Cl. D52—10)

To all whom it may concern:

Be it known that I, Henry Dreyfuss, a citizen of the United States, residing at New York city, in the county of New York and State of New York, have invented a new, original, and ornamental Design for an Over and Under Indicator for a Weighing Scale, of which the following is a specification, reference being had to the accompanying drawing, forming part thereof.

In the drawing, the figure is a perspective view

of an over and under indicator for a weighing scale showing my new design. The rear and opposite side of the indicator have the same general appearance as the front and side shown.

I claim:

The ornamental design for an over and under indicator for a weighing scale, as shown and described.

HENRY DREYFUSS.
